Primary Examiner — Cathron C Brooks*Assistant Examiner* — Ian F Whitmore(74) *Attorney, Agent, or Firm* — Hanley, Flight & Zimmerman, LLC(57) **CLAIM**

The ornamental design for a "touchscreen display with graphical user interface," as shown and described.

DESCRIPTION

The sole FIGURE is a front view of a touchscreen display with graphical user interface.

The outermost rectangular broken-line perimeter illustrates a touchscreen display and forms no part of the claimed design. The remaining broken lines illustrate portions of the graphical user interface and form no part of the claimed design.
